UNITED STATES PATENT OFFICE.

THEODORE J. P. F. LINDBERG, OF BROOKLYN, ASSIGNOR TO ROBERT S. GOULD, OF NEW YORK, N. Y.

METHOD OF ORNAMENTING CURTAIN-POLES.

SPECIFICATION forming part of Letters Patent No. 361,827, dated April 26, 1887.

Application filed December 16, 1886. Serial No. 221,728. (No model.)

To all whom it may concern:

Be it known that I, THEODORE J. P. F. LINDBERG, of Brooklyn, E. D., in the county of Kings and State of New York, have invented 5 a new and useful Improvement in Curtain-Poles and Method of Ornamenting the Same, of which the following is a full, clear, and exact description.

Reference is to be had to the accompanying 10 drawings, forming a part of this specification, in which similar letters of reference indicate corresponding parts in both figures.

Figure 1 shows a piece of a curtain-pole made in accordance with my invention; and 15 Fig. 2 is a transverse sectional elevation of the same, taken on the line *xx* of Fig. 1.

A represents the wooden portion of the curtain-pole round in cross-section. This is first covered or sheathed with sheet metal, B, in the 20 ordinary way—that is, by wrapping the metal in a plain state around the pole and inserting its edges in a small groove, *a*, in the pole. The surface of the sheathed pole is then ornamented by pressing a configuration, *b*, into the sheet- 25 metal sheathing and wood. In this instance the pole is ornamented by spiral ribs or depressions extending around the pole, and these

ribs or depressions are formed by passing the pole through a hollow revolving chuck having a point or tool to run in contact with the outer 30 surface of the pole. This tool compresses the metal sheathing and also the wood, as illustrated in Fig. 2, and the metal, being practically non-elastic, retains the impressions. In this manner the pole may be highly ornamented at very small additional cost. 35

Having thus described my invention, what I claim as new, and desire to secure by Letters Patent, is—

The method herein described of forming and 40 ornamenting curtain and similar poles, which consists in first covering a round wooden pole with plain sheet metal and securing the edges to the pole, and then passing the pole and covering through a hollow revolving chuck 45 provided with a point or tool to run in contact with the metal for impressing spiral ornamentation therein and embedding the metal into the wood, substantially as described.

THEODORE J. P. F. LINDBERG.
